MINE LOCOMOTIVE MOTOR TORQUE ARM

Loy D. Hagenbook, Chicago, Ill., assignor to
 Goodman Manufacturing Company, Chicago,
 Ill., a corporation of Illinois

Application April 14, 1945, Serial No. 588,355

9 Claims. (Cl. 105—132.1)

1

This invention relates to improvements in mine locomotives, and more particularly relates to an improved form and arrangement of support for the motors of an electric mine locomotive.

In electric mine locomotives, which are usually of a short wheel and spring base, there is a tendency for the pull on the drawbar of the locomotive to tilt the locomotive frame. This may reach such proportions as to be extremely objectionable and may be so great as to unbalance the frame.

The principal objects of my present invention are to overcome tilting of the locomotive frame by the pull of the drawbar thereon, by providing a novel form and arrangement of motor support so arranged that the motor reactions will offset the tendency of the drawbar pull on the locomotive frame to tilt the frame.

My invention may be more clearly understood with reference to the accompanying drawings wherein:

Figure 1 is a diagrammatic side view of a locomotive constructed in accordance with my invention;

Figure 2 is an enlarged fragmentary side view of the locomotive shown in Figure 1;

Figure 3 is an enlarged fragmentary plan view of the locomotive;

Figure 4 is an enlarged detail view showing certain details of the motor support in substantially longitudinal section; and

Figure 5 is a schematic illustration of a locomotive frame and stabilizer showing the forces acting thereon.

Fig. 5a is a force diagram for Fig. 5;

Fig. 6 is a schematic illustration of one of the motor assemblies 11; and

Fig. 7 is a fragmentary perspective view of Fig. 2.

In the embodiment of my invention illustrated in the drawings, a mine locomotive is shown as including a frame 10 supported on axles 11, 11 and track wheels 12, 12, through springs 13, 13 and equalizer mechanisms 14, 14. Said frame includes a pair of parallel spaced side plates 15, 15 connected together at their forward and rear ends by means of suitable bumpers (not shown) and by floor plates 16, 16, which with said bumpers and side plates form end cabs for the locomotive. Coupling members 17, 17 are suitably secured to said bumpers and extend therefrom and form a means for taking the drawbar pull of the locomotive.

The axles 11, 11 are each journaled at their ends in journal boxes 19, 19, which are slidably mounted between vertically extending guide

2

plates 20, 20 of pedestals 21, 21 formed in the side plates 15 of the locomotive frame. Said axle boxes are engaged at their upper ends on opposite sides of the side plates 15, 15 by equalizing bars 23, 23 extending along the inner and outer sides of said side plates and connected together at their forward and rear ends. Said equalizing bars are likewise connected together intermediate their ends by means of connecting members 10 24, 24 extending through openings 25, 25 in the side plate 15 and forming seats for the springs 13, 13. Said springs extend upwardly within said openings and engage members 27, 27 mounted in the upper sides of the openings 25, 25 and 15 forming seats for the upper ends of said springs. The ends of said equalizing bars project beyond said axle boxes, and said projecting ends are each herein shown as being connected with a fluid operated snubber 29. Said snubbers are mounted 20 in openings 30, 30 formed in each side plate 15, through which the ends of said equalizers extend, and form a means for snubbing the action of the springs 13, 13.

Each axle 11 has a motor 31 journaled thereon in a well known manner. Said motors extend rearwardly from said axles towards each other and are herein shown as being electric motors of a well known form having drive connection with their respective axles through spur gear trains 32, 32 enclosed in gear casings 33, 33. The drives from said motors to said axles are of a well known form and are no part of my present invention so are not herein shown or described in detail.

Each motor 31 is shown as having a pair of parallel spaced connecting members 35, 35 extending therefrom towards the center of the locomotive, which connecting members are herein shown as being formed integral with the motor casing. Each pair of said connecting members has a yieldable motor support link 36 pivotally connected therebetween on a pivotal pin 37.

Each motor support link 36 includes a cylinder 39 having an ear 40 projecting therefrom and pivotally connected between the connecting members 35, 35 on the pivotal pin 37. A plunger 41 is extensibly mounted within said cylinder. Said plunger is pivotally connected at its outer end between a pair of support members 42, 42 mounted on and depending from a cross frame member 43, connected between the insides of the side plates 15, 15. A compression spring 44 mounted within said cylinder is provided to yieldably restrain said plunger from movement with respect to said cylinder in either direction. Said com-

pression spring encircles a sleeve 45 mounted on said plunger and abuts a collar 46 held to the inner end of said plunger by means of a nut 47. The opposite end of said spring abuts a collar 48 mounted on said sleeve and abutting a shouldered portion 49 of said plunger, and also abutting a retaining cover 50 threaded on the outer end of said cylinder. The collar 46 also abuts a shouldered portion 51 of said cylinder to cause said spring to yieldably restrain inward movement of said plunger with respect to said cylinder.

The point of connection of the outer end of the plunger 41 (Fig. 4) to the support member 42 is so positioned that the motor support reactions through the motor support link 36 will be transferred to support member 43 on a line extending longitudinally through motor support link 36 and intersecting a line extending through the centers of the two axles 11 at a predetermined distance from the axle upon which the respective motor is mounted. This distance is such as to counteract the tendency of the drawbar to tilt the locomotive frame and applies when either one or two motors are provided to drive the locomotive. This distance is determined by the relationship

$$(1) \quad X = \frac{B}{2} \frac{r}{H}$$

where

B=wheelbase of the locomotive

r=radius of track wheels, and

H=height of the center of pull on the drawbar above the locomotive rails.

The above Equation 1 may be derived as follows:

First, referring to the Figs. 2 and 5 and assuming the locomotive frame 10, equalizer bars 14 and springs 13 together comprise a free body which is entirely independent of the wheel and motor assembly.

Let

P=backward force exerted on the locomotive by the drawbar pull.

R=reaction of force P exerted through link 36.

(For simplicity, this reaction initially will be considered as applied entirely through the left-hand link 36 (Fig. 5) instead of divided between the two links).

R_v=upward component of R.

V₁ and V₂=upward components of R_v as exerted through rear and front axles, respectively.

L=length of lever arm determined by distance from center of rear axle to the axis along which reaction R is acting.

X=distance from the rear motor axle to the point on the wheelbase line where the motor support reaction causes the frame to remain in equilibrium (i. e., where V₁=V₂).

The approach to the derivation is to express V₁ and V₂ in X plus known terms, then equate the expressions, and solve for X.

For convenience, because it eliminates consideration of the horizontal components of R through the axles 11, moments of the forces acting on the body are taken about M which is located on the wheelbase line midway between the axles. Three forces are involved: P, acting on lever arm (r-H). V₁, acting on lever arm

$$\frac{B}{2}$$

And V₂, acting on lever arm

$$\frac{B}{2}$$

Equating these moments about M,

$$(2) \quad P(r-h) + V_1 \frac{B}{2} = V_2 \frac{B}{2}$$

5 This simplifies to

$$(2a) \quad P(r-h) = \frac{B}{2} (V_2 - V_1)$$

Now, considering moments taken about the front axle, since the couple V₁B is generated by the couple R_v(B-X), they are necessarily equal, thus:

$$(3) \quad V_1 B = R_v (B-X)$$

Likewise, considering moments taken about the rear axle, since the couple V₂B is generated by the couple R_vX, they are necessarily equal, thus:

$$(4) \quad V_2 B = R_v X$$

Rearranging, Equations 3 and 4 become

$$(5) \quad V_1 = \frac{R_v (B-X)}{B}$$

$$(6) \quad V_2 = \frac{R_v X}{B}$$

Since R_v is an unknown it will be expressed in terms of X plus knowns as follows: Consider Fig. 6 which treats the rear motor assembly alone as a free body. There are five forces acting on this free body.

- Body weight acting downward through the axle.
- Reaction upward from the rail acting through the axle.
- Horizontal force acting backward from the body through the axle.
- Reaction R acting along link 36 on lever arm L, and
- Frictional force P' (equal to P) acting along rail on lever arm r.

In equating the moments about the above free body, the first three forces may be disregarded if the moments are taken about the rear axle itself. Thus,

$$(7) \quad RL = P'r$$

and, because P'=P,

$$(8) \quad RL = Pr$$

Since R_v is the vertical component of R,

$$(9) \quad RL = R_v X$$

Substituting (9) and (8),

$$(10) \quad R_v X = Pr$$

Rearranging

$$(11) \quad R_v = \frac{Pr}{X}$$

Now substituting (11) in (5) and (6),

$$(12) \quad V_1 = \frac{Pr(B-X)}{BX}$$

$$(13) \quad V_2 = \frac{\frac{Pr}{X}X}{B} = \frac{Pr}{B}$$

Substituting the above values of V₁ and V₂ in Equation 2a,

$$(14) \quad P(r-h) = \frac{B}{2} \left[\frac{Pr}{B} - \frac{Pr(B-X)}{BX} \right]$$

$$(15) \quad 2(r-H) = r - \frac{r(B-X)}{X}$$

$$(16) \quad 2r - 2H = r - \frac{rB}{X} + \frac{rX}{X}$$

$$(17) \quad 2H = \frac{rB}{X}$$

$$(1) \quad X = \frac{Br}{2H}$$

Q. E. D.

It will be seen from the foregoing derivation that the couple produced by the drawbar pull, which tends to rotate the locomotive frame in a counterclockwise direction, equals the couple produced by a single motor and motor frame 34 which tends to rotate the locomotive frame in a clockwise direction when the relationship expressed in the above Equation 1 is met.

For two identical drive motors, the balancing reaction force R' required in each link 36 will be half that required if only a single link is utilized.

This may be proved, with the aid of Figs. 5, 5a and 6, by assuming there are two, identical motor arrangements, each being equally effective to exert a reactive force R' through its corresponding link 36 on a lever arm Y to equalize the drawbar moment $P(r-H)$. In other words,

$$(18) \quad 2R'Y = P(r-H)$$

Now, since $R=2R'$

$$(19) \quad RY = P(r-H)$$

The above relationship may be proved by solving independently for Y , substituting the value of Y in Equation 19, and reducing one side of the equation to equality with the other as follows:

The value of Y may be determined from similar triangles in Figs. 5 and 5a, as follows

$$(20) \quad Y = \frac{L}{Z} = \frac{L}{X}$$

or

$$(22) \quad Y = \frac{LZ}{X}$$

By inspection of Fig. 5a,

$$(23) \quad Z = X - \frac{B}{2}$$

Substituting for Z in (22)

$$(24) \quad Y = \frac{L\left(X - \frac{B}{2}\right)}{\frac{B}{2}}$$

Substituting for X , from Equation 1,

$$(25) \quad Y = \frac{L\left[\frac{Br}{2H} - \frac{B}{2}\right]}{\frac{Br}{2H}}$$

Now, going back to Equation 19 and substituting for Y

$$(26) \quad \frac{RL\left[\frac{Br}{2H} - \frac{B}{2}\right]}{\frac{Br}{2H}} = P(r-H)$$

From Equation 8,

$$\frac{RL}{r} = P$$

Substituting on the left side of (26) and simplifying

$$(27) \quad \frac{P\left(\frac{r}{H} - 1\right)}{\frac{1}{H}} = P(r-H)$$

$$(28) \quad P(r-H) = P(r-H)$$

Q. E. D.

Thus, the relationship expressed in Equation 19 is proved, thereby demonstrating that the relationship

$$X = \frac{Br}{2H}$$

is applicable to both two- and four-wheel drive locomotives for effectively, positively and automatically counteracting the tilting moments created by the drawbar pull.

It may be seen from the foregoing that a simplified form of motor support has been provided for the motors of an electric locomotive, which is so arranged that the line of motor support reaction passes through a line extending through the centers of the two axles at such distances from the axles as to exactly counteract the effect of the drawbar pull of the locomotive to tilt the locomotive frame.

While I have herein shown and described one form in which my invention may be embodied, it will be understood that the construction thereof and the arrangement of the various parts may be altered without departing from the spirit and scope thereof. Furthermore, I do not wish to be construed as limiting my invention to the specific embodiment illustrated, excepting as it may be limited in the appended claims.

I claim as my invention:

40. 1. In a short wheel base electric locomotive having a main frame, track wheels and two longitudinally spaced axles yieldably supporting said main frame, an electric motor journaled adjacent one of its ends on one of said axles, gearing 45 connecting said motor with said one axle for driving said axle from said motor, coupling means for taking the drawbar pull of the locomotive at a point spaced vertically from an extended line extending through the centers of said axles, and 50 support means for said motor so arranged as to hold said motor from turning about said one axle and to neutralize the tipping effect of the drawbar pull on said main frame including a 55 motor support member extending from said motor and connected with said main frame at such an angle that the line of motor support reaction passes through a line intersecting a line extending through the centers of the two axles at a predetermined distance from the axle 60 on which said motor is mounted.

2. In a short wheel base electric locomotive having a main frame, a drawbar on said main frame, track wheels and two longitudinally spaced axles, spring means for supporting said main frame on said track wheels and axles, an electric motor journaled on one of said axles adjacent one of its ends, gearing connecting said motor with said one axle for driving said axle from said motor, said drawbar taking the drawbar pull of the locomotive at a point spaced vertically from an extended line extending through the centers of said axles, and support means for said motor so arranged as to hold said motor from turning about said one axle and to neutralize the tipping effect of the drawbar pull on said main

frame including a motor support member connecting said motor to said main frame and so arranged that the line of motor support reaction intersects a line which passes through the centers of said two axles at a predetermined distance from the axle on which said motor is mounted, said distance being substantially determined by the formula

$$\frac{B}{2} \times \frac{r}{H}$$

where B is the wheelbase of the locomotive, r is the radius of the locomotive wheels, and H is the height of the drawbar above the rail.

3. In a short wheel base electric locomotive having a main frame, a drawbar on said main frame, two axles having track wheels thereon, spring means for supporting said main frame on said track wheels and axles, an electric motor journaled adjacent one of its ends on one of said axles, gearing connecting said motor with said one axle for driving said axle from said motor, said drawbar taking the drawbar pull of the locomotive at a point spaced vertically from an extended line extending through the center of said axles, and means for holding said motor from turning about said one axle and neutralizing the tipping effect of the drawbar pull on said main frame including a bracket on said main frame, and a motor support connected between said motor and said bracket, said motor support extending at such an angle with respect to said motor that its line of motor support reaction substantially passes through a line intersecting a line passing through the centers of the two axles at a predetermined distance from the axle on which said motor is mounted, which distance is substantially determined by the formula

$$\frac{B}{2} \times \frac{r}{H}$$

where B is the wheelbase of the locomotive, r is the radius of the wheel, and H is the height of the drawbar above the rail.

4. In a short wheel base electric locomotive having a main frame, a drawbar on said main frame, two axles having track wheels thereon, spring means for supporting said main frame on said track wheels and axles, an electric motor journaled adjacent one of its ends on one of said axles, gearing connecting said motor with said one axle for driving said axle from said motor, said drawbar taking the drawbar pull of the locomotive at a point spaced vertically from an extended line extending through the centers of said axles, and means for yieldably holding said motor from turning about said one axle and neutralizing the tipping effect of the drawbar pull on said main frame including a bracket on said main frame and a yieldable motor support connected between said motor and said bracket, said motor support extending at an angle with respect to said motor and its line of motor support reaction passing through a line intersecting a line passing through the centers of the two axles at a distance substantially determined by the formula

$$\frac{B}{2} \times \frac{r}{H}$$

where B is the wheelbase of the locomotive, r is the radius of the wheel, and H is the height of the drawbar above the rail.

5. In a short wheel base electric locomotive having a main frame, a drawbar on said main

frame, two axles having track wheels thereon, spring means for supporting said main frame on track wheels and axles, an electric motor journaled adjacent one of its ends on one of said axles, gearing connecting said motor with said one axle for driving said axle from said motor, said drawbar taking the drawbar pull of the locomotive at a point spaced vertically from an extended line extending through the centers of said axles, and means for yieldably holding said motor from turning about said one axle and neutralizing the tipping effect of the drawbar pull on said main frame including a bracket on said main frame and a yieldable motor support link pivotally connected between said motor and said bracket, said motor support link extending at an angle with respect to said motor and its line of motor support reaction passing through a line intersecting a line passing through the centers of the two axles at a distance substantially determined by the formula:

$$\frac{B}{2} \times \frac{r}{H}$$

25 where B is the wheelbase of the locomotive, r is the radius of the wheel, and H is the height of the drawbar above the rail.

6. In a short wheel base electric locomotive having a main frame, a drawbar on said main frame, track wheels and two longitudinally spaced axles, spring means for supporting said main frame on said track wheels and axles, an electric motor journaled adjacent one of its ends on one of said axles, gearing connecting said motor with said one axle for driving said axle from said motor, said drawbar taking the drawbar pull of the locomotive at a point spaced vertically from an extended line extending through the centers of said axles, and means for yieldably holding said motor from turning about said one axle and neutralizing the tipping effect of the drawbar pull on said main frame including a member extending from said motor in a direction away from said one axle, a bracket on said main frame, and a yieldable motor support link pivotally connected between said member and said bracket, said motor support link extending at an angle to said member and its line of motor support reaction passing through a line intersecting a line passing through the centers of the two axles at a distance substantially determined by the formula

$$\frac{B}{2} \times \frac{r}{H}$$

55 where B is the wheelbase of the locomotive, r is the radius of the wheel, and H is the height of the drawbar above the rail.

7. In an electric locomotive, a main frame, a drawbar at each end of said main frame, track wheels and a pair of axles therefor, spring means for supporting said main frame on said track wheels and axles, an electric motor journaled on each of said axles, gearing connecting each motor with its associated axle, for driving said axles from said motors, and means counteracting the tendency of said motors to turn about said axles and neutralizing the tipping effect of the drawbar pull on said main frame including a motor support for each motor, said motor supports being connected between said main frame and said motors at such angles with respect to their motors that their lines of motor support reaction pass through a line intersecting a line passing through the centers of the two axles at

predetermined distances from the axles on which the motors are mounted, said distances being substantially determined by the formula

$$\frac{B}{2} \times \frac{r}{H}$$

where B is the wheelbase of the locomotive, r is the radius of the wheel, and H is the height of the drawbar above the rail.

8. In an electric locomotive, a main frame, a drawbar at each end of said main frame, track wheels and a pair of axles therefor, spring means for supporting said main frame on said track wheels and axles, an electric motor journaled on each of said axles, gearing connecting each motor with its associated axle, for driving said axles from said motors, and means counteracting the tendency of said motors to turn about said axles and for neutralizing the tipping effect of the drawbar pull on said main frame including a yieldable motor support for each motor, said motor supports extending in angular relation with respect to each motor and the lines of motor support reaction passing through a line intersecting a line passing through the centers of the two axles at distances substantially determined by the formula

$$\frac{B}{2} \times \frac{r}{H}$$

where B is the wheelbase of the locomotive, r is the radius of the wheel, and H is the height of the drawbar above the rail.

9. In an electric locomotive, a main frame, a drawbar at each end of said main frame, track wheels and a pair of axles therefor, spring means for supporting said main frame on said track wheels and axles, an electric motor journaled on each of said axles, gearing connecting each

motor with its associated axle, for driving said axles from said motors, and means counteracting the tendency of said motors to turn about said axles and for neutralizing the tipping effect of the drawbar pull on said main frame including a yieldable motor support for each motor in-
cluding a member projecting from each motor in a direction away from the axle on which said motor is journaled, a pair of brackets on said main frame, and yieldable links pivotally connected between said members and said brackets, said links being pivotally connected to said members for pivotal movement about substantially coaxial axes and the line of motor support re-
action through said links intersecting a line passing through the centers of the two axles at distances from the respective axles on which said motors are mounted determined substan-
tially by the formula

$$\frac{B}{2} \times \frac{r}{H}$$

where B is the wheelbase of the locomotive, r is the radius of the wheel, and H is the height of the drawbar above the rail.
